UNITED STATES PATENT OFFICE

2,438,298

LIQUID ELEVATING APPARATUS

Jesse C. Reed, Dayton, Ohio

Application June 29, 1946, Serial No. 680,410

5 Claims. (Cl. 103—72)

1

This invention relates to liquid-elevating apparatus, having particular reference to that type of such apparatus in which an endless belt is disposed for operation in a well shaft, and wherein the upper portion of the belt is passed around a motor-actuated driving pulley arranged in a casing above the well shaft, and wherein the lower part of the belt passes around a weighted pulley submerged in the liquid to be elevated and disposed in the bottom of the shaft, the arrangement being such that when the belt is actuated, liquid adheres to the surfaces thereof and is conducted upwardly for discharge from the apparatus when the belt passes around the upper or driving pulley. Such apparatus has been disclosed, in general, in my prior patent, No. 2,391,642, dated December 25, 1945.

As such apparatus has been constructed heretofore, the same has necessitated the employment of a rigid frame, depending from the casing at the top of the well shaft, for effecting the support of the lower pulley around which the liquid-submerged lower end of the endless belt passes. The employment of this rigid depending frame adds considerably to the cost of the apparatus and the length of the same is subject to variation in meeting the requirements of well shafts of different depth.

One of the objects of the present invention is to provide liquid-elevating apparatus of this character in which the depending well-shaft frame is eliminated and wherein cable-suspended means are provided, controllable from the top of the well shaft, for maintaining the lower pulley member of the apparatus in its required operating position.

Another object of the invention is to provide novel means, in liquid-elevating apparatus of the type under consideration, for maintaining the liquid-elevating belt under required tension and preventing twisting or undue distortion of the belt when positioned in a well shaft.

A further object of the invention is to provide a cable-suspended weight member for tensioning the liquid-elevating belt and, further, to provide said weight member and the lower belt pulley with a plurality of pivotally mounted arms, the latter carrying at their lower ends a plurality of sharp-edged disks, the arrangement being such that when the apparatus is suspended in a well shaft, the arms are actuated to maintain the sharp peripheral edges of the disk in contact with the well shaft lining, whereby to preclude rotation on the part of the lower belt pulley and twisting of the belt and without the employment of a rigid frame structure in the well.

For a further understanding of the invention, reference is to be had to the following description and the accompanying drawing, wherein:

Fig. 1 is a vertical sectional view, partly in side 60 verse shaft 30 which is journaled, as at 31, in

2

elevation, of liquid-elevating apparatus formed in accordance with the present invention;

Fig. 2 is a transverse vertical sectional view taken on the plane indicated by the line 2—2 of Fig. 1;

Fig. 3 is an enlarged vertical longitudinal sectional view taken through the upper portion of the apparatus;

Fig. 4 is a horizontal sectional view on the line 10 4—4 of Fig. 1.

Fig. 5 is a front elevational view, partly in vertical section, of the lower belt pulley and depending structure, disclosing a modified form of linkage for restraining the pulley against axial rotation.

Referring more particularly to the drawings, the numeral 1 designates the vertical bore or shaft of a well, containing liquid in the bottom thereof to be elevated, the bore or shaft being provided with the usual lining or casing 2, the open upper end of the bore or shaft being surrounded by a base 3 on which is mounted a housing or casing 4. The latter may consist of a base section 5 having an opening 6 formed in the top thereof. Positioned on the base section is a top section 7 provided with a removable cover plate 8.

The top section is formed with longitudinally aligned bearings 9 for the reception of a shaft 10, the latter passing through a stuffing gland 11 and being united by means of a flexible coupling 12 with the shaft of an electric motor 13, or other prime mover, which may be carried by a shelf 14, forming a part of the base section 5 and projecting laterally therefrom.

Between the bearings 9, the shaft 10 is provided with an upper or drive pulley 15 and passing around this pulley is one or more endless belts 16.

The ascending and descending runs of the belt 16 depend in parallel order in the shaft casing 2, and at its lower end the belt passes around a bottom pulley or guide sheave 17, the latter being rotatably mounted on a cross shaft 18.

Positioned as at 19 on the reduced outer ends 45 of the shaft 18 is a pair of arms 20, and the lower ends of these arms are pivotally joined, as at 21, to the upper ends of a pair of oppositely disposed bell crank levers 22. These levers are pivotally mounted on the intermediate portions of a shaft 23 which has its outer end portions positioned in registering openings 24 formed in the bifurcated upper end 25 of a weight member 26. The extreme outer ends of the shaft 23 are connected as at 27 with the lower ends of a pair of cables 28, the latter being employed in raising and lowering the weight member and the parts associated therewith.

To this end, the upper portions of the cables 28 are connected with drums 29 fixed on a transverse shaft 30 which is journaled, as at 31, in

the lower section 5 of the top housing. One end of the shaft 30, exteriorly of the housing, may be equipped with a crank 32 and a ratchet wheel 33, the teeth of the latter being engaged by the free end of a pawl 34 pivotally mounted on the exterior of the housing. The lower bifurcated arms of the bell crank levers 22 rotatably support knife-edge disks 35, which, as shown more particularly in Figs. 1 and 4, are normally adapted for engagement with the inner surfaces of the shaft lining or casing 2.

In operation, by rotating the shaft 30, the weight structure and its associated arms, together with the lower pulley 17, may be lowered into the well. When the pulley or shaft 17 reaches its fully lowered position as determined by the length of the belt 16, applying tension to said belt, the upper ends of the bell crank levers 22, through the arms 20, are oscillated inwardly about the axis of the shaft 23, causing the lower bifurcated ends of said bell cranks to swing outwardly, thus bringing the sharpened peripheral edges of the disks 35 into cutting or retaining contact with the inner wall surfaces of the shaft lining or casing 2. As a result of this action, the weight structure and the pulley or shaft 17 are restrained against rotation axially of the well shaft, holding the lower pulley in parallelism with the upper or drive pulley and preventing twisting of the liquid-elevating belt. When so positioned, the lower pulley will be immersed in the liquid in the bottom of the well to be elevated, so that when the power of the motor 13 is applied to the upper pulley, the resultant movement of the belt will cause liquid adhering therewith to be elevated and discharged from the top of the belt as it passes around the drive pulley 15. This liquid may be received in a pump chamber 36 formed in the housing 4 and permitted to gravitate to a point of discharge or, optionally, the said chamber may be equipped with a pump 37, driven by the shaft 10, or its equivalent, for the purpose of forcing the liquid to a more elevated point of usage.

It will be noted that in this construction, the employment of a rigid supporting frame, depending from the top housing, for carrying the lower pulley, is eliminated, thus readily adapting the apparatus to well bores of different depth and reducing the weight and costs of the apparatus, as well as simplifying the installation thereof.

In the modification disclosed in Fig. 5, the shaft 18 of the lower pulley or belt wheel carries at its ends a bail 40. To the lower and central portion of this bail there is pivotally connected, as at 41, the links 20 which in turn, have their lower ends pivoted as at 21 to the lever arms 22 in the same manner as disclosed in the preferred form of the invention.

While I have described what I consider to be the preferred form of my invention, nevertheless, it will be understood that the same is subject to certain modification or variation without departing necessarily from the spirit and scope of the following claims.

I claim:

1. Apparatus for elevating liquids from underground wells, comprising a housing arranged substantially at ground level above such a well, a driving pulley rotatably mounted in said housing, a continuous belt having its upper portion passing around said pulley, a second pulley disposed in the well and around which the lower portion of said belt passes, a weight arranged below said second pulley, lever arms pivotally carried by

said weight, devices carried by said arms at their lower ends adapted for engagement with the sides of the well, and means linking said arms at their upper ends with said lower pulley.

2. Apparatus for elevating liquids from underground wells, comprising a housing arranged substantially at ground level above such a well, a driving pulley rotatably mounted in said housing, a continuous belt having its upper portion passing around said pulley, a second pulley disposed in the well and around which the lower portion of said belt passes, a weight arranged below said second pulley, lever arms pivotally carried by said weight, devices carried by said arms at their lower ends adapted for engagement with the sides of the well, means linking said arms at their upper ends with said lower pulley, drum means rotatably mounted in said housing, and cables having their upper ends connected with said drum means and their lower ends united with said weight.

3. Apparatus for elevating liquids from wells, comprising a housing arranged substantially at ground level above such a well, a driving pulley rotatably mounted in said housing, a continuous belt having its upper portion passing around said pulley, said belt depending therefrom into said well and having its lower portion submerged in the well liquid to be elevated, a second pulley disposed in the well and around which the lower portion of said belt passes, a weight member arranged below said second pulley, drum means rotatably supported by said housing, cables having their upper ends connected with said drum means and their lower ends with said weight member, lever arms pivotally carried by said weight member, links pivotally uniting said arms at their upper ends with said second pulley, and disks having sharpened peripheral edges carried by said arms at their lower ends, the edges of said disks being adapted for engagement with the sides of the well to restrain the belt and the lower pulley against turning movement axially of the well.

4. Apparatus for elevating liquids from underground wells, comprising a housing arranged above such a well, a driving pulley rotatably mounted in said housing, a continuous belt having its upper portion trained around said pulley, said belt depending therefrom into said well with its lower portion submerged in the well liquid to be elevated, a lower pulley including an axial shaft disposed in said well and around which the lower portion of said belt passes, a weight member arranged below said lower pulley, drum means rotatably supported by said housing, cables having their upper ends connected with said drum means and their lower ends with said weight member, pivoted links carried by said pulley shaft, and means connected with said links and engageable with the sides of the well and actuated by relative movement between said weight member and said lower pulley to restrain the belt and the lower pulley against turning movement axially of the well.

5. Apparatus for elevating liquids from casing lined wells, comprising a housing arranged above such a well, a driving pulley rotatably mounted in said housing, a continuous belt trained around said pulley and depending therefrom into said well, the lower portion of said pulley being adapted for submergence in liquid contained in the well, a second pulley supported on and around which the lower portion of said belt is trained, and an axially disposed shaft carried by said second

pulley, a weight member arranged below said second pulley, drum means rotatably supported by said housing, cables having upper ends connected with said drum means and lower ends connected with said weight member, links pivotally carried by the ends of the shaft of said second pulley, bell crank levers pivotally carried by said weight member, said levers having their upper ends pivotally connected with said links at the lower ends of the latter, and disks having sharpened peripheral edges carried by said levers at their lower ends, the edges of said disks being adapted for engagement with the well casing to restrain the

belt and lower pulley against turning movement axially of the well.
